CLAIM

The ornamental design for a shoulder pad for carrying skis, as shown and described.

DESCRIPTION

FIG. 1 is a front elevational view of a first embodiment of

a shoulder pad for carrying skis showing my new design;

FIG. 2 is a rear elevational view thereof;

FIG. 3 is a top plan view, with the bottom plan view being a mirror image thereof;

FIG. 4 is a left side view, with the right side view being a mirror image thereof;

FIG. 5 is a perspective view, with the straps shown in a closed position;

FIG. 6 is a front elevational view of a second embodiment;

FIG. 7 is a rear elevational view thereof;

FIG. 8 is a top plan view, with the bottom plan view being a mirror image thereof;

FIG. 9 is a left side view, with the right side view being a mirror image thereof; and,

FIG. 10 is a perspective view, with the straps shown in a closed position.
